UNITED STATES PATENT OFFICE.

WILLIAM A. READE, OF CLEVELAND, OHIO, ASSIGNOR TO THE LUDLOW TYPOGRAPH COMPANY, OF CLEVELAND, OHIO, A CORPORATION OF MAINE.

MOLD FOR TYPOGRAPHS.

1,106,112.

Specification of Letters Patent.

Patented Aug. 4, 1914.

Application filed February 27, 1911, Serial No. 811,246. Renewed November 29, 1913. Serial No. 803,859.

To all whom it may concern:

Be it known that I, WILLIAM A. READE, a citizen of the United States, and a resident of Cleveland, county of Cuyahoga, and 5 State of Ohio, have invented a new and useful Improvement in Molds for Typographs, of which the following is a specification, the principle of the invention being herein explained and the best mode in which I have 10 contemplated applying that principle, so as to distinguish it from other inventions.

The present improvements relate to a modification of the so-called Ludlow typograph, whereby it may be adapted to cast 15 slugs, or lines-of-type, of greater transverse width than the ordinary line so as to accommodate larger type of the kind frequently desired for printing head-lines and advertisements. By this means the necessity for 20 maintaining a stock of "sorts" is done away with at a considerable saving of expense and room since with an ordinary font of matrices any amount of large type matter may be set up, whereas in the case of advertisements, a whole page is blocked out in 25 large type. I am aware that it has heretofore been sought to cast slugs with initial letters larger than the body face, by simply placing the matrix of the larger letter, or 30 other character, so as to overlap the front face of the mold. The slug thus formed will have a thin, overhanging body of metal bearing such larger character on its face, which overhanging portion is adapted to extend 35 over the face of an adjacent, smooth slug. Although such extended character may be thus supported from below, it is, nevertheless, so thin that it has a tendency to curl, especially on cylinder presses and 40 when subjected to hard use.

The object of the present invention is to avoid the difficulty just noted and provide a slug fully as strong and durable as the ordinary one of uniform thickness throughout. 45 To the accomplishment of this and related ends, said invention then consists of the means hereinafter fully described and particularly pointed out in the claims.

The annexed drawings and the following 50 description set forth in detail certain mechanism embodying the invention, such disclosed means constituting, however, but one of various mechanical forms in which the principle of the invention may be used.

In said annexed drawings:—Figure 1 is 55 a transverse section through a mold and the adjacent parts of a typograph embodying my present improvements; Fig. 2 is a plan view of the form of construction of the mold shown in Fig. 1; Fig. 3 illustrates a 60 modified form of construction of mold; Fig. 4 is a transverse section on the line 4—4, Fig. 2; Fig. 5 is a similar section of the modified form of mold on the line 5—5, Fig. 3; Fig. 6 illustrates in end elevation, an assembled body of slugs of the kind made by means of my improved mold; Fig. 7 is a sectional view corresponding with Fig. 1, but showing the mold arranged for casting blank slugs; Fig. 8 is an inverted perspective view of a member forming part of this modified construction; Fig. 9 illustrates in transverse section yet another use to which the invention is adapted; and Fig. 10 is a perspective view of a slug cast therein.

In the arrangement of the parts illustrated in Fig. 1, the form of mold there appearing is shown in association with a supporting bed 1, which may be the "trough" of the Ludlow typograph as at present constructed, or with any other suitable support; whereon the matrix bars 2 are adapted to rest. For the casting of slugs of the kind under consideration, matrix bars, each having only a single character 3, are ordinarily used, these short bars replacing the longer bars with a number of matrices which are regularly employed. It should further be borne in mind that the present improved construction of mold is susceptible of use in conjunction with any approved style of casting mechanism, and the matrix bars may be supported directly on the mold face under certain conditions. To hold said matrix bars properly together in their assembled condition a frame 4, preferably of rectangular form, is provided; while similarly a presser foot 5 or equivalent means, is employed to clamp said bars against the mold face during the actual casting operation. The molten metal is designed to be supplied to the mold from beneath, only the nozzle 6 of the casting pot and the terminal "squirt plate" 7 carried by said nozzle, appearing in the figure in question.

The mold 8 differs from preceding constructions in that in place of a simple rectangular slot being provided therein to re-

ceive such molten metal and thus form the slug, such slot is enlarged at its upper end. This enlargement preferably extends equally on each side of the main body of the slot and 5 is of a width equal to, or preferably somewhat larger than, the maximum width of the large sized type that are to be formed thereon. This enlargement is secured by a removable plate 12 with a slot 13 that provides for the enlargement in the assembled 10 condition of the parts. When such plate is in position, it will be observed that a ledge or off-set is left on each side of the first-named slot of standard dimensions between 15 the same and such enlarged slot-portion.

As illustrated in Fig. 6 the slug 9 formed by a mold of this construction is of considerably larger width in its upper portion than in the body proper, such upper portion supporting or carrying the character 10 formed by the matrix on its upper face. The latter is thus cast upon a solid body of metal and does not consist of a thin strip-like extension from the relatively narrow body of 25 the slug.

In assembling the slugs into a column for printing, blanks 11 of a proper size to fit beneath the shoulders of the enlarged slug portions are utilized to fill out the spaces between the slug bodies.

Where it is desired to vary the width of the enlarged slug portions to suit characters of different widths, as where more than one kind of headline or large type is used, it is 35 only necessary to remove the plate 12 and substitute a second plate having a larger or smaller slot 13, as is required under the circumstances. By thus taking off one plate and substituting another, the mold may 40 be readily changed to cast slugs with enlargements of different widths and when it is desired to cast slugs having a normal width, a plate may be substituted having a slot of the same dimensions as the slot in the 45 mold.

In Fig. 3, I have illustrated a modified form of plate for casting a slug with an enlarged upper portion. Here the plate consists of two sections 14, 14, relatively adjustable transversely of the slot in the mold 8, proper, so as to provide a slot of any desired width within predetermined limits. The outer limit of adjustment will of course correspond with the maximum size of type 50 which it is desired to cast, while the inner limit will similarly correspond with the width of the body portion of the mold-slot, which of course is that of the standard line.

By means of the foregoing construction it 60 will be obvious that not only may slugs be cast with enlarged type with the greatest facility, but that the slugs formed in this fashion are of superior quality both in durability and in the clearness of the impression which they are capable of giving by

reason of the solid support afforded the characters on their faces.

It has already been indicated that the casting mechanism may be variously arranged, while still retaining the advantageous features of the improved mold constituting the present invention; there being no intention, in referring to a particular typograph, to imply a limitation in the adaptability of such mold.

The blanks 11, which are utilized as above described in assembling the slugs into the form to fill out the spaces between the slug bodies, may be either carried in stock, or else cast as desired with the same mold by closing 75 the mold aperture or slot in the fashion indicated in cross section in Fig. 7. For this purpose I preferably employ a block 15 having its dimension at right angles to the line of section as great as that of the mold face 80 and having a depending lug 16 adapted to rest on the ledges formed between the main or body portion of the mold slot and the enlarged portion thereof so as to close completely the opening of such body portion of 85 the mold slot. Where blanks thus formed are to be utilized, the overhanging portions of the slug formed in the fashion previously set forth must, of course, be respectively equal in transverse width to the thickness of the 90 body portions of the slug formed in such body portion of the mold.

Where a line of type is desired, terminating short of the ends of the slug body, members 17 similar to the block 15, but narrower, 95 may be utilized to close the corresponding portions of the mold opening. The lugs 18 on these members, however, will require to extend entirely across the enlarged upper portion of such mold opening (see Fig. 9) 100 in order to prevent the molten metal from escaping past. Furthermore, such lug, unlike lug 16, stops short of the bottom of the enlarged mold portion, so as not to interrupt the continuity of the web that constitutes the enlarged portion of the completed slug, as shown in Fig. 10. Said members 17 will, in other respects, resemble the matrix bars 2, which carry the matrices for the casting of the type, and are assembled 110 along with such bars as indicated in the sectional view of Fig. 9, being capable of interposition between words in the line as well as of use in closing the ends of the line. A slug formed with such interposed and 115 mold closing members is illustrated in Fig. 10.

The several novel elements entering into the form and construction of the slugs or type bars, which may be made by my improved typograph mold, as hereinbefore described, have been held to constitute a separate invention from such mold, and so are described and claimed in another application filed by me July 3, 1914, Serial No. 848,764. 125 130

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

- 10 1. A mold for casting slugs, or lines of type, comprising a body formed with a casting slot of standard dimensions, and a plate secured to the face of said mold-body and formed with a slot registering with but 15 larger than such first-named slot.
- 20 2. A mold for casting slugs, or lines of type, comprising a body formed with a casting slot of standard dimensions, and a plate secured to the face of said mold-body and formed with a slot registering with but 25 larger than such first-named slot, all such enlarged slot extending equally on each side of the smaller slot.
- 30 3. A mold for casting slugs, or lines of type, comprising a body formed with a casting slot, and adjustable means secured to the face of said mold body adapted to form a slot of variable size in register with such first-named slot.
- 35 4. A mold for casting slugs, or lines of type, comprising a body formed with a casting slot, and a sectional plate secured to the face of said mold-body the sections of said plate being adjustable to form a slot of variable size in register with such first-named slot.
- 5 5. A mold for casting slugs, or lines of type, comprising a body formed with a cast-

ing slot of standard dimensions, and a plate secured to the face of said mold-body and including two sections transversely adjustable on such face so as to form a slot of variable size in register with such first-named slot.

6. A mold for casting slugs, or lines of type, comprising a body formed with a casting slot of standard dimensions, and a plate secured to the face of said mold-body and including two sections of L-shape transversely adjustable on such face so as to form a slot of variable size in register with such first-named slot.

7. The combination with a mold for casting slugs, or lines of type, formed with a casting slot of standard dimensions and an enlarged portion opening onto the casting face of said mold, a ledge being left on each side of such first-named slot between the same and such enlarged slot portion; of a member adapted to rest on such ledges and thereby close such first-named slot.

8. The combination with a mold for casting slugs, or lines of type, formed with a casting slot of standard dimensions and an enlarged portion opening onto the casting face of said mold; of matrix-bars adapted to rest against such mold face across such enlarged slot-portion; and other bars having depending lugs adapted to fit into such enlarged slot-portion.

Signed by me this 16th day of February, 1911.

WILLIAM A. READE.
